United States Patent Office

Des. 189,485
Patented Dec. 27, 1960

189,485

HOBBYHORSE

Joseph Palma, Jr., River Forest, Ill., assignor to Manning Manufacturing Corporation, Chicago, Ill., a corporation of Illinois

Filed May 31, 1960, Ser. No. 60,794

Term of patent 14 years

(Cl. D34—15)

Fig. 1 is a perspective view of a hobbyhorse embodying my new design.

Fig. 2 is a front elevational view thereof.

Fig. 3 is a rear elevational view thereof.

The undisclosed side of the hobbyhorse is substantially as shown in Fig. 1.

I claim:

The ornamental design for a hobbyhorse, substantially as shown and described.
